CARBON STRIPPING DEVICE

James W. Anderson, Niagara Falls, N. Y., assignor
to Gilman Fanfold Corporation, Niagara Falls,
N. Y., a corporation of Delaware

Application September 27, 1935, Serial No. 42,449

27 Claims. (Cl. 197—126)

This invention relates to typewriting machines and equipment for typewriting machines, and, with respect to its more specific features, it relates to the transfer or carbon equipment for such machines and to parts of typewriting machines in their aspects of controlling the transfer equipment and the worksheets associated with the transfer, or carbon, sheets.

One object of the invention is the provision of a simple and practical form of carbon-stripper, or transfer-stripper, which may be of the standard length of carbon strippers heretofore employed for typewriting machines, and which nevertheless has a greatly increased transferring capacity and longevity.

Another object of the invention is the provision of a simple and efficient form of carbon-stripper employing a plurality of superposed carbon sheets and wherewith the position of said sheets relative to each other is under positive control and which is adapted to relieve many objectionable frictional or binding effects hitherto encountered in connection with manifold equipment in typewriting machines.

Another object is the provision of a simple and practical form of carbon-stripper whereby the structure of typewriting machines of the Wernery and Smith type, as exemplified in U. S. Patent No. 1,132,055, patented March 16, 1915, may be much simplified, as by omission of the platen lifting or platen swinging feature and its attendant details.

Another object of the invention is the provision of an efficient and simple form of carbon-shifter capable of use in machines of the Wernery and Smith type aforesaid, whether said platen-lifting or platen-swinging feature be or be not retained in such machine.

Another object of the invention is the provision of a simple and practical construction of carbon, or transfer, equipment which readily accommodates itself to the many different manipulations of the worksheets attendant upon the operation of typewriting machines.

Another object is to provide an efficient, simple and practical construction of carbon-stripping device useful in various different types of typewriting machines.

Another object is the provision of a practical, simple and efficient form of combined worksheets and carbon-stripper as a supply device for typewriting machines.

Another object is the provision of a simple and practical form of transfer, or carbon, sheet for use in typewriting machines.

Another object of the invention is the provision of an efficient and practical carbon-stripper for use in typewriting machines and having simple and improved features promotive of elimination of the binding effect of the carbon leaves on the worksheets and constructed so that fresh carbon surfaces may readily be supplied by mere manipulation of the carbon leaves of the stripper itself and without the addition of extra carbon leaves.

Other objects of the invention will be in part obvious and will in part appear hereinafter.

The invention accordingly comprises the features of construction, combination of elements and arrangement of parts which will be exemplified in the construction hereinafter set forth, and the scope of the application of which will be indicated in the claims.

For a more complete understanding of the nature and objects of the invention, reference is had to the following detailed description and to the accompanying drawings in which:

Fig. 1 is a diagrammatic perspective view illustrative of an ordinary typewriter carriage and platen and showing applicant's carbon-stripper associated with relatively superposed worksheets, as at the beginning of typing the advance worksheet sections;

Fig. 2 is an enlarged, vertical cross-section through Fig. 1, showing the worksheets and carbon-stripper, after being typed, advanced from the position of Fig. 1, the stripper being in checked position;

Fig. 3 is a similar cross-section to Fig. 2, but shows the feed pressure rolls depressed and the worksheets advanced relative to the stripper and the most advanced typed section torn off;

Fig. 4 is an enlarged detail of Fig. 2 or Fig. 3;

Fig. 5 is a perspective view of one construction of carbon-stripper embodying the present invention, the thickness of the transfer, or carbon, sheets being exaggerated for clearer disclosure;

Fig. 6 is a longitudinal section centrally of Fig. 5;

Fig. 7 is a perspective of a single stripper-sheet of Fig. 5, and looking at the face of the sheet opposite from that seen in Fig. 5;

Fig. 8 is a perspective view illustrating a modified construction of stripper-sheet which may be employed, the thickness of sheets being exaggerated as in the other figures, and a portion being cut out to illustrate detail construction;

Fig. 9 is a longitudinal sectional view as in Fig. 6, and showing the path of the worksheets relative to the stripper-sheets. In Fig. 9, the

spaces between the worksheets and stripper-sheets are exaggerated for disclosure. This Fig. 9 also diagrammatically illustrates the associated worksheets and carbon-stripper in general relation as a supply device for typewriting machines; 5

Fig. 10 illustrates in perspective some parts of the checking device;

Fig. 11 is a transverse section of a portion of the stripper showing a fastener element of the 10 checking device;

Fig. 12 is a perspective view illustrative of worksheets associated for use as a supply for typewriting machines embodying this invention;

Fig. 13 is a perspective view of a stripper sheet 15 similar to that of Fig. 7 but slightly modified;

Fig. 14 is a perspective view of a portion of a stripper generally similar to that of Fig. 1 but modified in some features;

Fig. 15 is a perspective view of a stripper embodying this invention associated with a machine of the type of the Wernery and Smith Patent 1,132,055;

Fig. 16 is a vertical, longitudinal section through a portion of the machine of the Wernery 25 and Smith patent with the stripper of the present invention embodied therein;

Fig. 17 is a view generally similar to Fig. 16 but illustrating the stripper and worksheets in a different position; and

30 Fig. 18 is a view showing a portion of the Wernery and Smith machine embodying the present invention, the platen being shown in full lines in lifted position, and the sheets being straightened out, as customary in the Wernery and Smith machine.

Referring now more specifically to the drawings, the platen carriage of an ordinary typewriting machine which is reciprocally shiftable in letter-spacing direction is illustrated in Fig. 1, 40 the numeral 1 indicating the side pieces of the carriage frame in which is journaled the cylindrical platen 2, rotatively shiftable in forward line-spacing direction by actuation of the line-space mechanism of the machine (not shown) 45 and in the opposite direction by grasping the hand wheel or knob 3. Numerals 4 indicate the lower feed rolls which are movable toward and from the platen to grip and release the worksheets and any interposed transfer sheets. The 50 feed rolls 4 may be moved by turning the pivoted hand lever 5, in one direction, and the latter actuates cam 6 to shift the feed roll carrier 7 around its pivot 8 to lower the feed rolls and retain them in position in which the worksheets 55 are released from the feed-grip of the platen and these feed rolls (see Fig. 3). Actuation of the lever 5 in the opposite direction shifts or turns cam 6 in the opposite direction permitting spring 9 to shift the feed roll carrier in direction 60 to lift the feed rolls 4 into worksheet-gripping cooperation with the platen for feeding the gripped worksheets when the platen is rotated in either direction (see Fig. 2). A type bar of usual construction and operation is indicated for 65 typing the worksheets at the typing line of the machine, shown at 10. As the construction and operation of ordinary typewriting machines are well known, it is deemed unnecessary to illustrate the entire machine. It is also to be understood 70 that the machine parts herein illustrated are merely exemplary and indicative of parts of typewriting machines the construction and operation of which are well known. Numeral 11 indicates the rear paper table of the machine, 75 which may have a rounded upper end 12.

The paper record sheets or strips, herein referred to generally as worksheets, are continuous and may be as long as desired. The supply of worksheets may come from any suitable source, as from a roll or rolls, or from a pack 5 or packs of zigzag folded worksheets. In Fig. 12, three worksheets 13 are shown in superposed relation coming from a zigzag supply pack 14, in which latter the three worksheets are interfolded as a unit in a zigzag manner, heretofore well known. Each worksheet is preferably divided into successive sections by a longitudinal series of transverse, equi-spaced weakening lines 15, which may be perforations whereby the sections may readily be torn apart. Or a knife or tearing-bar may be employed. Though three worksheets are illustrated, it will be understood that a greater or lesser number may be employed. In the usual and preferred practice, each worksheet has a longitudinal series of similar printed 20 forms 16. For the typing operation, a plurality of the worksheets are superposed with the printed forms and weakening lines of the different sheets in registry in superposed relation so that typing on the original worksheet may be 25 duplicated in the same relative position on underlying worksheets and so that the weakening or tear-off lines 15 of different worksheet sections will arrive in substantial registry at tear-off position in the typewriting machine. 30

A feature of the invention concerns the provision of a carbon stripper, the carbon or transfer sheets of which may be of merely normal length but also may be shifted about so as to be used either end foremost and thus provide 35 for utilizing the fresh transfer material of one transfer section of the transfer sheet when that of the other transfer section has become depleted. In the preferred construction, the stripper includes a plurality of relatively superposed 40 carbon, or transfer, sheets 17, each of which may be merely an integral transfer, or carbon, sheet, of any of the usual materials heretofore employed for transferring typing. The ordinary manifolding paper coated with carbon transfer 45 material, heretofore commonly used in typewriting machines, is suitable for the purpose.

In order to avoid certain binding effects on the worksheets, and to promote the shifting about of the stripper-sheets, as will hereinafter appear, the present invention contemplates threading the underlying worksheets through an aperture or opening in the stripper intermediate the fore and aft ends thereof. As shown in Fig. 5, each stripper-sheet, or transfer-sheet 17, has an opening or aperture 18, for threading the underlying worksheets therethrough, and the transfer sheets 17 are attached together so as to control the relation of the apertures 18 to each other and also the relation of the transfer, or stripper, sheets 17, to each other, as will hereinafter appear. As it is designed to provide for easy relative shift movement between the transfer sheets and the worksheets threading 60 through the apertures 18, said apertures should be of sufficient extent both longitudinally and transversely to admit of the free and unobstructed passage of a relatively large number of worksheets which may be employed. The dimensions of the apertures longitudinally of the sheets may be relatively larger than required for easy passage of worksheets, and it is preferred to have the transverse dimension somewhat comparative but greater than the width of the 70

worksheets for general guiding effect of the apertures on the worksheets.

It will be perceived that the apertures 18 divide the stripper-sheets 17 each into fore and aft sections 19 and 20. Each such section has transfer material for manifolding use. Each transfer section, fore and aft of the aperture 17, is of area sufficient for manifolding cooperation with a worksheet section or printed form 16, ahead of the aperture so the operator may rely upon obtaining copy on underlying worksheets of entries typed on the original worksheet. While it is preferred that the transfer area shall be coextensive with the stripper-sheets 17, both lengthwise and widthwise, it is to be understood that some departure from complete coating is permissible under certain conditions, as where the entire length of printed forms 16 is not to be typed. It is a distinct and important advantage, however, to employ stripper-sheets 17 which are completely coated with transfer material throughout, as such sheet material is readily available. And in conjunction with the apertures 18, complication in operation of the stripper is avoided.

When the apertures 18 are made within the transfer or carbon area of an integral transfer sheet, and completely through the sheet, as illustrated in Fig. 5, there is assurance that these apertures 18 are bonded fore and aft by transfer material, which latter will lie close to the edges of the apertures in each sheet, so that manifolding typing may be done as close to the edge of the aperture as desired. Also, as these apertures are at times concealed, it is preferred that the fore end of the aperture register with the weakening line 15 or be close thereto during typing so that the operator, by observing the position of the weakening line 15 as the latter approaches the typing line, may be guided as to the approach of the aperture to the typing line.

As illustrated, the stripper-sheets are attached together and provide a compact, unitary pack of relatively superposed manifolding transfer sheets. Any means lending itself to the operation of the invention may be used for securing the transfer sheets together. As shown in the drawings, the stripper-sheets are firmly connected together aft of the apertures by cooperative snap-fastener members 21 and 22, the headed fastener pins 21 passing through fastener openings 23 in the superposed stripper-sheets and being removably gripped and retained in the resiliently acting fastener sockets 22. These fastener members 21 and 22 may be of known construction and made of relatively rigid metal. They secure the transfer sheets together against substantial longitudinal movement relative to each other; they maintain the apertures 18 at predetermined distances from the line of attachment between the transfer sheets when the stripper is in operative relation and they control the relation of the apertures of different transfer sheets to each other.

As illustrated, the apertures 18 of different transfer sheets are in superposed registry and such is the preferred arrangement, as it is simple and makes for convenient threading of the worksheets through the different transfer sheets and through the stripper. However, other relative positions of the apertures may be employed within the scope of this invention (see Fig. 14).

A device or means is provided for checking, or arresting, the advance of the transfer sheets 17 in their course around the platen. Within the

broader aspects of this invention, the checking device may take numerous forms. A practical construction may include the relatively rigid bar 25 which is detachably secured or connected to the pack of transfer sheets on the platen-side of the latter. The bar 25 is preferably disposed at the end of the aft sections 20, of the pack and remote from the worksheet-threading apertures 18. As illustrated this bar 25 serves as a mounting or carrier for the fastener sockets 22, the latter being suitably secured to bar 25. The checking device may also include a worksheet guiding and supporting device including the relatively rigid plate or member 26 having recurving ends 27, on which latter the fastener-pins 21 may be mounted as illustrated. Member 26 provides a loop through which all the relatively superposed worksheets loosely pass on their approach to the apertures 18. The bar 25 and plate 26 each provide also for bracing the pack of transfer sheets transversely when attached to the pack.

At each of the opposite ends of each transfer-sheet 17 is a foldable, transversely disposed extension 28 integral with the sheet 17. This extension may be folded to position opposite the main body of this sheet 17, as on the dotted line 29, at which the sheet 17 may be creased if desired. The so folded extension 28 is shown in Figs. 6 and 9, the fastener openings 23 being so located on opposite sides of the line of fold as to register with each other after the extension is folded. The fastener pins 21 pass through the contiguous folded ends of the relatively superposed transfer sheets 17. The length of the stripper-sheets or transfer-sheets, in the preferred embodiment of the invention, should be sufficient to provide a foldable extension 28 at each end of the sheets 17 in addition to the operative length of the two transfer sections 19 and 20.

The preferred course or path of the worksheets coming from the pack 14 or other supply is readily understood from the drawings. The superposed, continuous worksheets may pass through the aforesaid loop and run beneath or outside the rear or aft sections 20, of all the transfer sheets. The upper worksheet 13 is then threaded through the apertures so as to be adapted to lie against the cylindrical or curved platen 2 and opposite the fore section 19 of the immediately adjacent transfer sheet 17. The intermediate worksheet 13 is threaded through the aperture 18 in the outer transfer sheet and disposed between the fore sections 19 of the two transfer sheets. The original, or outer, worksheet may continue its position opposite to but outside the fore sections 19 of both transfer sheets without entering the apertures 18.

The assembled worksheets and stripper afore described provide a manifolding supply device for introduction to and use in typewriting machines. Having introduced the advance ends of the worksheets and interleaved fore sections of the transfer sheets between the platen 2 and feed rolls 4, the stripper and worksheets will occupy typing position for manifolding substantially as shown in Fig. 1. Preferably the advance edges 30 of the worksheets will be arranged sufficiently ahead of the advance edges of the transfer sheets 17 as to permit the worksheets to be grasped as a unit without grasping the transfer sheets. But these advance edges may be otherwise related.

Typing now begins, the typing line being indicated by the arrow 31. Imprint on the original worksheet will be effected by the usual type-

writer ink ribbon and line spacing will be accomplished in the manner and by the mechanism well known in typewriting machines. As line-spacing proceeds, the checking-device also advances with the transfer sheets 17 and may ride over the end 12 of the rear paper table to position between this table and the platen, and until further advance of the transfer sheets is checked or arrested by the platen and paper table preventing further advance of the checking device. The operator may effect the aforesaid operations by the usual line spacing mechanism or by grasping and pulling the worksheets forward. As line-spacing proceeds the apertures 18 also advance or shift around the platen 2 toward the typing or printing line, 31.

Having finished typing on the advance set of worksheet forms, it will be desired to then dispose the transfer sheets in interleaved relation with the succeeding set of worksheet forms. In the conditions prevalent in typewriting machines having curved platens, the path of the worksheets and transfer sheets is a curved path around the platen. When the transfer sheets are checked as aforesaid, and it is attempted then to advance the worksheets to bring the succeeding set of worksheet forms to interleaved manifolding relation with the fore sections of the transfer sheets, said fore sections, being curved, cooperate with the platen to bind the underlying worksheets so strongly that advance shift of the worksheets relative to the transfer sheets may not be effected so long as said binding effect prevails. One of the important objects of the present invention is to relieve or entirely remove said binding effect on the worksheets, so that the latter may be grasped at their ends and readily advanced relative to the transfer sheets thereby to interleave the transfer sheets with the succeeding set of worksheet forms or worksheet sections next to be typed.

In Fig. 2, the numeral 32 indicates an advance set of typed worksheet forms. The extended ends of these forms are grasped, without grasping the transfer sheets, and pulled forward to position out of manifolding relation to the transfer sheets 17, as shown in Fig. 3 at 33. Such operation has also advanced the superposed, continuous work-sheets 13 until the next succeeding set of worksheet forms 16 is brought to manifolding relation with the fore sections 19 of transfer sheets 17, as shown in Fig. 3. Thereupon, the set 33 may be torn-off or sheared from the continuous worksheet on weakening lines 15. Preliminary to advancing or forwardly shifting the worksheets relative to the transfer sheets at the platen from the Fig. 2 relation, the fore-sections 19 of the transfer sheets are disposed so that the portions 34 thereof forming the advance boundaries of the apertures 18, lie substantially in a line tangent to the platen at the point where the worksheets are to be advanced relative to the transfer sheets. The line of pull, or pull-line, in advancing the worksheets relative to the transfer sheets, may be straight up, as in Figs. 2 and 3, or inclined either rearwardly or forwardly cross-wise of the platen 2, and the tangent point on the platen may be at different locations circumferentially of its curved surface, dependent on the direction of said pull-line. Said pull-line is usually straight, adjacent the advance edges of the apertures, and the transfer-sheet areas or sections 34 immediately ahead of the apertures lie parallel to this pull line.

When the advance ends of the apertures reach

said tangent point the binding effect of the transfer-leaves on the worksheets is greatly relieved, as the worksheets thread through the stripper-sheets or transfer-sheets to the outside of the transfer leaves, and no substantial curved area of the transfer leaves is bound by the platen. 5

The checking device hereinbefore mentioned may be disposed relative to the transfer leaves 17 so as to check advance shift of the transfer 10 or carbon sheets at or after the advance boundaries or edges of the apertures reach said tangent relation. And in practice the apertures 18 are so related to the worksheet forms that manifold typing of a complete set of forms may be effected 15 before the apertures 18 reach the typing line and before the checking device is arrested by the platen and rear paper table. Having finished typing, whether the whole or part of the length 20 of a set of worksheet forms, the operator advances the assembled worksheet and transfer sheets, as a unit, until the transfer sheets are checked. This may be done either by rotating the platen by its handle 3, or by pulling the assembled sheets. When checked the apertures 25 are preferably above the typing line 31, as shown in Figs. 2 and 3, and the subsequent pull on the worksheets should be in a direction not to cause sufficient curving around and against the platen of the worksheets and fore sections of transfer 30 sheets ahead of the apertures 18 to restore any substantial binding effect on the worksheets. By securing the transfer sheets together, the relation of the apertures 18 of different sheets to the tangent point and line of pull is controlled. 35

In the Fig. 3 position the worksheets have been pulled or shifted ahead as described above, while the stripper-sheets are checked. During such shift the feed pressure rolls 4 are in their lower or releasing position, having been previously shifted by the operator. 40

Both the fore and aft sections of the transfer leaves have transfer material for manifolding, and the length of these sheets and disposition of transfer material thereon are such that 45 they may be secured or attached together and also disposed relative to the worksheets with either of the ends of either transfer sheet in advance relation to its opposite end. The stippling, Figs. 1, 5 and 8, indicates the transfer face of 50 the sheets. Ordinarily, and as shown, the transfer material is confined to the faces of the transfer leaves that face the platen 2, but it may be on both faces or on the front face only, though the latter are not preferred. Both the fore and aft sections of the transfer leaves being manifolding sections, not only do these leaves provide a much greater length of transfer material for the stripper without requiring any increase in the length of the stripper leaves, but the leaves 60 of the stripper may be confined to ordinary carbon or transfer leaf material such as the thin, carbon paper of commerce, so that practically the full length of the stripper is of manifolding material usable for copying imprint of typing. 65

By means of a stripper-sheet having the transfer material at each side, fore and aft of the apertures, it will be perceived that either the section of stripper in advance of where the worksheet threads through the aperture or the section 70 in the rear thereof, may be disposed in manifolding relation to the worksheet, as selected, or when the advance transfer section becomes depleted. The provision of attaching the checking device to the stripper-sheets 17 either fore or aft 75

of the edges of the apertures 18, enables the stripper to be shifted end for end so that either section of the stripper-sheets may be interleaved with the worksheets, as shown, for instance, in Figs. 1, 2 and 3, the other section of the stripper taking up position outside and above the worksheets, as also illustrated in the same figures. Thus, means is provided cooperable for attaching the stripper-sheets to the stripper in either 10 of two positions, in one of which it is in reverse position relative to its other position, and in each of such positions, the fore and aft transfer sections respectively will lie at opposite sides of a worksheet threading through the apertures. 15 Furthermore, by disposing the aperture centrally of the stripper-sheets, the checking device may be located at a predetermined distance from the advance edge of the aperture in either the direct or reversed position of the stripper. And it will 20 be observed that in either the direct or reversed relation of the stripper-sheets, the position of the apertures therein is controlled by the checking device in its relation relative to the tangent point and the pull-line hereinbefore referred to. 25 Whereas in this description, the sections 19 have in the main been termed the fore or advance sections, and the sections 20, the aft or rear sections, it is to be understood that these terms relate to the relative disposition of said sections 30 as assembled for operation in the typewriting machine, or in the supply device, and that either section may be related as an advance section, the other section thus becoming related as the rear section. 35 In case of contemplated wear on the fore and aft edges of the apertures 18, a wear-protective layer 35 may be applied close to the fore and aft bounding margins of these apertures, and on the face opposite the transfer face. This layer 35 40 may be of very thin, flexible paper pasted to the sheets 17 and lying close to and preferably flush with the said fore and aft edges, as indicated in Fig. 7. In Fig. 7 it is observed that the thickness of the transfer sheet and of the wear-protective 45 layer thereon, has been exaggerated for the purpose of clearer disclosure.

It will be understood that other forms of stripper embodying the general principle described herein are within the purview of this invention. 50 For instance, instead of providing fore and aft sections of the stripper-sheet as an integral sheet, they may be fabricated from wholly separate sheets, as in Fig. 8, where the numeral 36 indicates a separate and individual transfer sheet attached to the equally separate and individual transfer sheet or section 37, by short strips of thin, flexible paper 38, the strips 38 being pasted to the back of the respective sections 36 and 37, and holding the sheets or sections 36 and 37 in 55 relation to provide the space 39 therebetween, which space corresponds and operates similarly to the apertures 18 in the form previously described.

In the embodiment illustrated in Fig. 7, the 60 wear-reducing layer 35 is illustrated as having an opening and a continuous border around said opening. In Fig. 8, a similarly shaped wear-protective layer may be employed to attach the fore and aft transfer sections 36 and 37 together. 65 While in the description, the transfer sheets referred to are ordinarily of paper coated with carbon transfer material, it is to be understood that the sheet material may be other than paper and the transfer material thereon may be such 70 as desired which is capable of manifolding im-

print by typing, as usual in typewriting machines.

It will be further perceived that the stripper-sheets of this invention may be substituted for the ordinary carbon sheets which are fastened to the shiftable carbon holder, as described in said Wernery and Smith Patent No. 1,132,055, and that upon said substitution, the typewriting machine of the Wernery and Smith patent, and other similar machines, may be operated as described in said patent, including the operation of lifting the platen to straighten out the worksheets and carbon leaves, or the Wernery and Smith machine may be operated and relative shift between the carbons and worksheets effected without lifting said platen. 15

The numerals 40 indicate transfer sheets according to the present invention, but somewhat longer than the transfer sheets shown in Fig. 5, in order that they may be associated with the reciprocally shiftable carbon holder 41 of said 20 Wernery and Smith machine.

Referring to Figs. 15, 16, 17 and 18, it will be understood that the parts of machine illustrated in these figures represent the same parts of the machine in said Wernery and Smith patent. 25 Reference is made to said Wernery and Smith patent for a full description of such machine, it being felt that it is unnecessary to embody the entire machine herein. It may be noted, however, that in order to provide for adjustment of 30 the point at which the carbon holder 41 is stopped in its forward reciprocal movement in the Wernery and Smith machine, the upstanding pin abutment or stop member 42 (Fig. 16) is provided and is secured by an easily manipulated 35 pin 43, the pin 43 being adjustable back and forth to different positions in the slot 44 in the frame member 45 of the machine. It will be perceived that by adjusting the position of the abutment 42, the position at which the holder 41 40 is arrested on its forward movement may be selectively changed. In Fig. 17 the holder is shown in position against the abutment 42. Any satisfactory adjustment abutment or stopper may be used. 45

In the long transfer sheets 40, which preferably have straight side margins, as indicated at 46, apertures 47 are provided which are similar to and have a similar purpose as the apertures 18 in the transfer sheets 17 heretofore described. 50 The apertures 47 in the two transfer sheets are in superposed registry with each other. Another set of apertures 48 disposed rearwardly of the apertures 47 may also be provided, the apertures 48 being for the same purpose as the apertures 55 47 and 18. In its broader aspect, it is to be understood that one set of apertures in the two sheets 40 may be used, as for instance, the apertures 47. Under such circumstances, the stop 42 will be set in position such as to arrest the 60 advance of the holder 41 and the transfer sheet 40 at the point where the apertures 47 or the advance margins thereof are tangent to the platen, as hereinbefore explained in connection with the apertures in the transfer sheets 17. 65

Fig. 16 represents the position of the holder and the transfer sheets and associated worksheets in position ready for typing at the beginning of a set of worksheets, the previously typewritten set having been shifted or stripped relative to the transfer sheets and torn off or parted on the knife blade 49, as indicated in dotted lines in Fig. 16. In Fig. 17 the associated worksheets and transfer sheets have been shifted forwardly 70 as a unit, typing of the advance set of forms hav- 75

ing been finished, and it will be seen that the apertures 47 in the transfer sheets occupy a position tangent to the pull-line as hereinbefore described. In the Fig. 17 position, the advance ends of the worksheets may be grasped without gripping the transfer sheets, and shifted forwardly relative to and while the transfer sheets are at rest, these latter being prevented from forward movement by the stop 42. During this relative shifting movement, the feed rolls 50 of the Wernery and Smith machine should be in shifted position so as not to clamp the worksheets against the platen. Thus the relative shift between the transfer sheets and the worksheets 10 to effect stripping is accomplished without lifting the cylindrical platen 51 of machines of the Wernery and Smith type.

Or said platen 51 may be lifted by the mechanism provided therefor, as described in the 20 Wernery and Smith patent, from the dotted line position indicated at 52 to the upper full line position indicated at 51, and thereby permit the associated worksheets and transfer sheets to straighten out, whereupon the worksheets may 25 be advanced relative to the transfer sheets to bring the next set of worksheet forms into manifolding relation with the transfer sheets, or the transfer sheets may be shifted rearwardly by the handle 52a (shown in dotted lines) which may 30 be fastened to the transfer sheet holder 41 for that purpose.

Numeral 53 indicates a spring motor and drum serving to coil a belt or cord 54 running over a pulley 55, the other end of the belt 54 being attached to the holder 41 for retracting the holder in an automatic manner. It is to be understood that the automatically retracting operation may be dispensed with, as for instance, by removing the belt 54 from attachment to the holder 41.

Referring to Fig. 14, in addition to the apertures 18, as shown in Fig. 5, one of the transfer sheets 17 is provided with an additional worksheet-threading aperture 56. The arrangement in Fig. 14 is merely exemplary of a different disposition of the apertures from that illustrated in Fig. 5. In Fig. 14, the underlying worksheet may be threaded through the apertures 18 in both the upper and lower transfer sheets 17, and the next adjacent worksheet threaded 45 through the aperture 56 in the outer transfer sheet 17 only. The position of the checking device 25 relative to the apertures 18 and 56, in the arrangement of Fig. 14, is preferably such that the aft set of apertures 18 may arrive at 50 the point on the platen tangent to the pull-line when the checking device is in arrested position between the platen 2 and the rear paper table 11.

In utilizing the invention in the Wernery and Smith type of machine, when the foremost sections 60 of the transfer sheets 40 ahead of the advance apertures 47 have become depleted of transfer material, said foremost sections 60 may be torn off or otherwise parted transversely through the apertures 47, as on the line 61, 65 thus eliminating the used sections 40. Thereupon the worksheets may be threaded through apertures 48, and the sections 62 of the sheets 40 become the fore sections thereof. The slot 44 in the frame should be long enough to permit adjustment of the arresting abutment 42 to position to check advance of holder 41 at or after the advance margins of the apertures 48 arrive at a point on the platen tangent to the pull-line, as heretofore described. It is furthermore to be understood that in the embodiment

of Fig. 15 instead of employing two sets of apertures longitudinally separated, a single set may be employed centrally of the lengths of sheets 40, whereupon the transfer sheets may be reversed end for end, and either end connected to the holder 41.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A carbon stripper having means, including a work-sheet-threading opening in a carbon sheet of the stripper cooperable for disposing transfer material of said carbon sheet in manifolding relation to the worksheets either end foremost.

2. A carbon stripper having means, including a work-sheet-threading opening in a carbon sheet of the stripper cooperable for disposing transfer material of said carbon sheet in manifolding relation to the worksheets either end foremost, and means, including a stripper-checking device, cooperable in either said relation of the transfer material.

3. A carbon stripper having a plurality of relatively superposed carbon sheets, means, including a worksheet-threading opening in each of a plurality of said carbon sheets cooperable for disposing transfer material of said carbon sheets in operative manifolding relation to the worksheets either end foremost, and means, securing said carbon sheets together, controlling the position of said openings in different sheets relative to each other.

4. A carbon stripper having a plurality of relatively superposed carbon sheets, means, including a worksheet-threading opening in each of a plurality of said carbon sheets cooperable for disposing transfer material of said carbon sheets in operative manifolding relation to the worksheets either end foremost, means, securing said carbon sheets together, controlling the position of said openings in different sheets relative to each other, and means, including a stripper-checking device, cooperable in either said relation of the transfer material.

5. A supply device for the purpose described including, in combination, a plurality of continuous worksheets in superposed relation to each other, a plurality of relatively superposed carbon sheets each having an opening through the sheet and transfer material fore and aft of said opening, one or more of said worksheets passing through an opening in a carbon sheet, the fore transfer sections of said carbon sheets facing one side of the worksheet or sheets passing through said opening and the aft transfer sections facing the opposite side thereof, and means securing said carbon sheets together controlling the relative position between said openings of different said carbon sheets.

6. A supply device for the purpose described including, in combination, a plurality of continuous worksheets in superposed relation to each other, a plurality of relatively superposed, carbon sheets each having an opening through the sheet and transfer material fore and aft of said opening, one or more of said worksheets passing through an opening in a carbon sheet,

the fore transfer sections of said carbon sheets facing one side of the worksheet or sheets passing through said opening and the aft transfer sections facing the opposite side thereof, means 5 securing said carbon sheets together controlling the relative position between said openings of different said carbon sheets, and a stripper-checking device connected to said carbon sheets.

10 7. A stripper for the purpose described having, in combination, a stripper-sheet, a stripper-checking device, and means cooperable for threading a worksheet through said stripper-sheet and selectively disposing either the section 15 of stripper-sheet in advance of where said worksheet is threaded or the section in rear thereof in manifolding relation to said worksheet, each said section having transfer material for manifolding.

20 8. A stripper for the purpose described having an opening for passage of a worksheet through the stripper, and having transfer material fore and aft of said opening, said stripper being reversible end-for-end and cooperable in either 25 reversed position for manifolding cooperation with a worksheet passing through said opening, a checking device, and means cooperable for connecting said checking device to the stripper and selectively disposing the checking device in 30 checking relation in either of the reversed positions of said stripper.

9. A stripper for the purpose described having, in combination, an integral stripper-sheet provided with an aperture for threading a worksheet through said stripper sheet, the sections of said stripper sheet fore and aft of said aperture having transfer material for manifolding.

10. A stripper for the purpose described having, in combination, an integral stripper-sheet 40 provided with an aperture for threading a worksheet through said sheet, the sections of said sheet fore and aft of said aperture having transfer material for manifolding, and means cooperable for attaching said stripper sheet to the 45 stripper in either of two positions, in one of which it is in reversed position, end-for-end, relative to its other position.

11. A stripper for the purpose described having, in combination, an integral stripper-sheet 50 provided with an aperture for threading a worksheet through said sheet, the sections of said sheet fore and aft of said aperture having transfer material for manifolding, and means cooperable for attaching said stripper sheet to the 55 stripper in either of two positions, in one of which it is in reversed position, end-for-end, relative to its other position, and in each of which positions said fore or aft sections, respectively, will lie at opposite sides of a worksheet threading through said aperture.

12. A stripper for the purpose described having, in combination, an integral stripper-sheet provided with an aperture for threading a worksheet through said sheet, the sections of said 65 sheet fore and aft of said aperture having transfer material for manifolding, a checking device, and means cooperable for attaching said stripper-sheet to said checking device either fore or aft of said aperture.

70 13. A stripper for the purpose described having, in combination, a plurality of relatively superposed stripper-sheets each provided with an aperture for threading a worksheet there-through and each having transfer material fore 75 and aft of said aperture therein, and means

controlling the relation of said stripper-sheets to each other.

14. A stripper for the purpose described having, in combination, a plurality of relatively superposed, integral carbon sheets having apertures therein for threading worksheets there-through, means securing said carbon sheets together, and a checking device attached to said stripper and disposed at a distance from said apertures. 10

15. A stripper for the purpose described having, in combination, a checking-device and a plurality of relatively superposed carbon sheets each having a worksheet-threading aperture through the carbon material so as to bound the 15 apertures fore and aft thereof by carbon material.

16. A stripper for the purpose described having, in combination, a checking-device, and a plurality of relatively superposed carbon sheets 20 each having a worksheet-threading aperture through the carbon material so as to bound the aperture fore and aft thereof by carbon material, and means selective for connecting said checking-device to said stripper and disposing 25 said checking device either fore or aft of said apertures.

17. A stripper for typewriting machines having, in combination, a plurality of relatively superposed carbon sheets, each having an aperture 30 for threading a worksheet through the carbon sheet, and transfer material fore and aft of said aperture, shiftable to different positions around the roller platen of the machine and to position in which the advance boundaries of the 35 apertures lie parallel to the straight pull-line of worksheet sections ahead of said apertures, and a checking-device cooperable to check advance shift of said apertured carbon sheets with said boundaries in said parallel relation to said pull-line. 40

18. A stripper for typewriting machines having, in combination, a plurality of relatively superposed carbon sheets each having an aperture 45 for threading a worksheet through the carbon sheet, and transfer material fore and aft of said aperture, shiftable to different positions around the roller platen of the machine and to position in which the advance boundaries of the 50 apertures lie parallel to the straight pull-line of worksheet sections ahead of said apertures, a checking-device cooperable to check advance shift of said apertured carbon sheets with said 55 advance boundaries in said parallel relation to said pull-line, and means controlling the relation of said stripper-sheets to each other.

19. A stripper for typewriting machines having, in combination, a plurality of relatively superposed carbon sheets, each having an aperture 60 for threading a worksheet through the carbon sheet, and transfer material fore and aft of said aperture, shiftable to different positions around the roller platen of the machine and to position in which the advance boundaries of the 65 apertures lie in a tangent to said platen at the point where the worksheets are to be advanced relative to said carbon sheets, and means attaching said apertured carbon sheets together and controlling the position of the apertures of different sheets relative to each other and said tangent point.

20. A stripper for typewriting machines having, in combination, a plurality of relatively superposed carbon sheets, each having an aperture for threading a worksheet through the car-

- bon sheet, transfer material fore and aft of said aperture, shiftable to different positions around the roller platen of the machine and to position in which the advance boundaries of the 5 apertures lie in a tangent to said platen at the point where the worksheets are to be advanced relative to said carbon sheets, means attaching said apertured carbon sheets together and controlling the position of the apertures of different 10 sheets relative to each other and said tangent point, and a checking-device cooperable to check advance shift of said carbon sheets at or after said advance boundaries reach said tangent relation.
- 15 21. A stripper for typewriting machines having, in combination, a plurality of relatively superposed carbon sheets each having an aperture for threading a worksheet through the carbon sheet and transfer sections fore and aft of 20 said aperture, each of area sufficient for manifolding cooperation with worksheet sections, ahead of said apertures, shiftable to different positions around the roller platen of the machine and to position in which the advance boundaries 25 of said apertures lie parallel to the straight pull-line of worksheet sections ahead of said apertures, a checking device cooperable to check advance shift of said apertured carbon sheets with said advance boundaries in said parallel relation 30 to said pull-line, and means cooperable for attaching said carbon sheets to said checking device and selectively disposing either the fore or aft edges of said apertures in advance position.
22. A stripper for typewriting machines having, in combination, a plurality of relatively superposed carbon sheets each having an aperture for threading a worksheet through the carbon sheet and transfer sections fore and aft of 35 said aperture, each of area sufficient for manifolding cooperation with worksheet sections, ahead of said apertures, shiftable to different positions around the roller platen of the machine and to position in which the advance boundaries of said apertures lie in a tangent to said platen 40 at the point where the worksheets are to be advanced relative to the carbon sheets, a checking device cooperable to check advance shift of said apertured carbon sheets after said advance boundaries reach said tangent relation, and 45 means cooperable for attaching said carbon sheets to said checking device and selectively disposing either of said transfer sections in advance position relative to the other.
23. A stripper for the purpose described having, in combination, a pack of manifolding sheets, each having a worksheet threading aperture intermediate its ends; each section fore and aft of, and from close to the edge of, said aperture being a transfer section, the opposite transverse 50 bounding margins of said apertures having a layer of relatively thin, flexible material for reducing wear on the edges of the apertures, and a checking device secured on said pack and disposed remote from said apertures.
24. A stripper for the purpose described having, in combination, a pack of manifolding sheets, each having a worksheet threading aperture intermediate its ends, each section fore and aft and from close to the edge of said aperture being 55 a transfer section, the opposite transverse bounding margins of said apertures having a layer of

relatively thin, flexible material for reducing wear on the edges of the apertures, and a checking device secured on said pack and disposed remote from said apertures, said apertures being relatively wide longitudinally of the sheets for free and unobstructed simultaneous passage of a relatively large number of worksheets through each apertured sheet. 5

25. A stripper for the purpose described having, in combination, a pack of manifolding sheets, each having a worksheet threading aperture intermediate its ends, each section fore and aft of and from close to the edge of said aperture being a transfer section, the opposite transverse bounding margins of said apertures having a layer of relatively thin, flexible material for reducing wear on the edges of the apertures, and a checking device secured on said pack and disposed remote from said apertures, the length of said manifolding sheets being sufficient to provide a foldable, transverse, securing extension at each end of the sheets in addition to the transfer sections aforesaid. 10 15 20

26. A stripper for the purpose described having, in combination, a pack of manifolding sheets each having a worksheet threading aperture intermediate its ends, each section fore and aft of and from close to the edge of said aperture being a transfer section, the opposite transverse bounding margins of said apertures having a layer of relatively thin, flexible material for reducing wear on the edges of the apertures, a checking device secured on said pack and disposed remote from said apertures, the length of said manifolding sheets being sufficient to provide a foldable, transverse, securing extension at each end of the sheets in addition to the transfer sections aforesaid, said apertures being located equidistant from said foldable extensions, the folded extensions being in superposed contiguous relation to each other, and said checking device comprising a sheet-bracing bar detachably affixed to said folded extensions at one end of the pack, and a worksheet-supporting loop underlying said pack. 25 30 35 40 45

27. A supply device for use in typewriting machines and the like having, in combination, a plurality of relatively superposed, continuous worksheets, a stripper having a plurality of relatively superposed carbon sheets with apertures through the carbon sheets, and carbon material fore and aft of the apertures, underlying worksheets lying threaded through said apertures and in interleaved, manifolding relation with the fore-sections of said carbon sheets 50 and all lying outside of said carbon sheets opposite the aft-sections thereof, said carbon sheets firmly secured together against relative longitudinal movement at a point aft of said apertures so as to maintain said apertures at predetermined distances from said point where secured, the length of and disposition of carbon material on said carbon sheets being such that they may be secured together and disposed relative to said worksheets as aforesaid and with either of the ends of the carbon sheets in advance relation to the opposite ends, and a checking device having means for detachably affixing it to said carbon sheets at a distance from said apertures. 55 60 65 70
